UNITED STATES PATENT OFFICE.

WILLIAM SPEARS, OF GOLDEN, COLORADO.

OIL PAN FOR INTERNAL-COMBUSTION ENGINES.

Application filed June 12, 1923. Serial No. 567,840.

To all whom it may concern:

Be it known that I, WILLIAM SPEARS, a citizen of the United States, residing at Golden, in the county of Jefferson and State of Colorado, have invented certain new and useful Improvements in Oil Pans for Internal-Combustion Engines, of which the following is a specification, reference being had therein to the accompanying drawing.

10 This invention relates to an improved oil pan for internal combustion engines and one object of the invention is to provide the oil pan with means for retarding the flow of lubricating oil longitudinally of the pan. 15 In an internal combustion engine of the splash feed type used upon Ford automobiles, the oil is conveyed from the oil reservoir at the rear of the crank case and deposited in a pipe which carries it forwardly 20 to the timing gear train. The oil after being projected upon the timing gear train drops downwardly into the crank case. As the oil moves rearwardly of the crank case to the oil reservoir, this oil passes over the 25 oil pan which closes an opening formed in the bottom of the crank case and fills troughs or pockets into which the connecting rods dip when the motor is in operation, and the crank shaft turning over. It has 30 been found that when going up hill, the oil in these troughs or pockets carried by the oil pan will have a tendency to move rearwardly out of these pockets thereby leaving the forward connecting rods and bearings unlubricated. In the same way, when 35 going down hill, the oil has a tendency to gather in the forward end portion of the crank case, thus causing excessive lubrication. In the present illustration, the oil 40 pan has been shown provided with a bridge or baffle plate which is secured to the oil pan between certain of the pockets or troughs and serving to prevent the oil from flowing rearwardly beyond a desired 45 amount and also serving to prevent oil in the oil reservoir from flowing forwardly into the forward end portion of the crank case. Therefore, the forward bearings and connecting rods will be properly lubricated 50 when going up or down hill, the same as they are when the machine is traveling on a level.

This invention is illustrated in the accompanying drawing, wherein:

55 Figure 1 is a view showing a motor principally in side elevation and partially in

longitudinal section and showing the oil pan provided with the oil retarding bridge or baffle plate.

Figure 2 is an enlarged transverse sec- 60 tional view taken along the line 2—2 of Fig. 1.

Figure 3 is a perspective view of the baf- 65 fle plate or bridge which is to be secured to the oil pan.

The internal combustion engine which is indicated in general by the letter E is of a conventional construction and provided with the crank case C having the customary opening formed in its bottom or underpor- 70 tion as shown in Figs. 1 and 2. This opening is provided with the usual bordering strip S having threaded openings formed therein to receive the bolts B which serve to secure the oil pan P to the underface of the crank 75 case. This oil pan is provided with the usual oil troughs or pockets P' and in a four cylinder motor will be three in number. As previously explained, the oil passes over the oil pan from one trough or pocket to the 80 other and finally passes into the reservoir R. In order to prevent the oil from flowing rearwardly out of the pockets and thus leaving the forward bearings unlubricated and also prevent the oil from flowing for- 85 wardly and gathering in the forward end portion of the crank case, there has been provided a bridge or baffle strip 1 which is formed of heavy sheet metal and provided at its lower end with a side extension or flange 90 2 having openings 3 formed therein to receive rivets 4 which pass through the oil pan as shown in Fig. 1. At its ends, this bridge or baffle plate is provided with ex- 95 tensions or wings 5 which extend in over- lapping relation to the bordering strip S and serves to assist in holding the oil pan in place. When putting the oil pan in place, it is necessary to position it at a suitable 100 angle which will permit the wings or end extensions 5 to pass upwardly through the opening in the bottom of the crank case and then turn the pan to the proper position, in which it covers the opening in the bottom of the crank case and the baffle extends trans- 105 versely of this opening as shown in Fig. 2 with the end extensions or wings 5 extending in overlapping relation to the bordering strip S. The bolts B will then be put in place and when tightened, will serve to se- 110 curely hold the oil pan in place. From an inspection of Fig. 1, it will be readily

seen that when going up or down hill, the oil which will have a tendency to flow longitudinally of the oil pan will strike the baffle and be retarded in its flow. Therefore, the oil will be prevented from moving out of a position in which the connecting rods can dip into the oil.

Although only one baffle plate has been shown, it is to be understood that additional 10 ones can be provided if found desirable.

I claim:

1. A crank case oil pan having oil pockets, and a baffle plate extending transversely of the oil pan between the oil pockets and having 15 its lower end portion secured to the oil pan between the oil pockets, the end portions of said baffle being extended to overlie portions of a crank case at the sides of an opening closed by said oil pan and support 20 the pan while fasteners for the pan are put in place.

2. A crank case oil pan, and means extending from the inner face of the pan for engaging the inner face of a crank case and 25 suspending said pan from the crank case

while fasteners for the pan are put in place.

3. A crank case oil pan, and means for suspending said pan from a crank case while fasteners for the pan are put in place, said

means serving as baffle means to retard flow 30 of oil longitudinally of said pan when the pan is secured to said crank case.

4. A crank case having an opening formed therein, an oil pan for closing said opening, removable fasteners for securing said pan to said crank case, and means carried by said pan for engaging said crank case and supporting the pan beneath the crank case during placing of said fasteners.

5. A crank case having an opening formed 40 therein, an oil pan for closing said opening, removable fasteners for securing said pan to said crank case, and means carried by said pan for engaging said crank case and supporting the pan beneath the crank case 45 during placing of said fasteners, said means being in the form of a baffle plate extending transversely of said pan to retard flow of oil longitudinally thereof, the end portions of said baffle plate being extended in spaced relation to the sides of the pan to overlie the crank case at the sides of the opening therein and suspend the pan beneath the crank 50 case.

In testimony whereof I hereunto affix my 55 signature.

WILLIAM SPEARS.
